ACCORDION

Nicola Turturro, New York, N. Y.

Application April 28, 1937, Serial No. 139,393

3 Claims. (Cl. 84—376)

This invention relates to accordions and particularly to the bass action mechanism therefor.

As heretofore constructed the bass action mechanism has required an immense amount of 5 hand labor to construct and properly adjust. One of the principal objects of this invention, therefore, is to simplify the construction and, at the same time, so to form many of the parts that they are capable of mass production and assembly by mass production methods.

Another difficulty with former types of construction is that they are difficult to assemble and disassemble, so that repairs to valve springs or leathers are long, tedious and expensive jobs. A 15 further object of the invention, therefore, is to construct the valve operating mechanism in a series of units which can be readily separated from and then brought back into operative relation with the other units.

One suitable form of construction is illustrated, 20 by way of example, in the accompanying drawing, wherein:

Fig. 1 is a vertical transverse section through the bass box; and

Fig. 2 is a top plan view of a part of the valves 25 and valve operating mechanism, portions being broken away.

As shown, 1 represents the bass action box having a valve panel 2, with a row of bass valves 3 and a row of melody or accompaniment valves 4 mounted thereon. The valves 3 are mounted on arms 5 pivotally mounted on the panel at 6 and normally held closed by wire springs 7. Similarly, the valves 4 are mounted on arms 8 30 pivotally mounted on the panel at 9 and normally held closed by wire springs 10. The free ends of the arms 5 and 8 are bent to cause the ends of the arms 8 to overlap those of the arms 5, so that, if one of the valves 3 is lifted off its seat, it also 35 raises the corresponding valve 4. On the other hand, if one of the valves 4 is lifted, the companion valve 3 remains closed.

The valves are lifted off their seats by two series of rods 15 and 16 rotatably mounted in a 40 chassis designated as a whole by 17. This chassis comprises end plates 18, side bars 19 and end bars 20.

Depending from these bars 15 and 16 are a series of hooks 22, and extending upwardly from the 45 valves 3 and 4 are a series of hooks 23, arranged so that when the chassis is in its proper place, as shown in Fig. 1, the ends of the hooks 22 underlie the ends of the hooks 23. When, however, the screws 24 which hold the chassis in position 50 are removed, and the latter is slid to the left (Fig.

1), the hooks 22 are moved clear of the hooks 23, so that the chassis can be lifted out of the bass action box. In assembling the mechanism the operation is reversed.

For turning the rods 15, shift bars 27 are provided, slidably mounted in slots in the side bars 19 and having the usual keys 28 at one end. These shift bars are formed of flat metal strips with recesses 29 cut or stamped out along their lower edges to receive the turned-over ends of 10 pins 30 attached to the rods 15. By sliding one of the shift bars 27 to the left, the shoulder at one end of the recess engages the pin 30 and causes the corresponding rod to turn and lift its 15 associated valve.

For turning the rods 16 a second set of shift bars 33 are provided, slidably mounted in a rectangular frame comprising side members 34 and end members 35. The ends of the side members 34 fit into recesses in the end plates 18 of the 20 chassis. The frame can be readily lifted off the chassis to expose the shift bars 27 and permit their removal. The chassis and the rods 15 and 16 carried thereby can then be removed.

The shift bars 33 are operatively connected to 25 the rods 16 by a series of rod bars 40. As shown, these rod bars consist of flat metal strips recessed along one side to leave projections 41 adapted to engage similarly formed projections 42 on the under side of the flat metal shift bars 33. Where 30 necessary to secure the proper combination of chords, in place of the short projections 41, long hooked projections 45 may be provided adapted to be engaged by the projections 42 corresponding to another bank of rod bars.

These rod bars each have an aperture at each 35 end through which extends the upper end of a pin 43 attached to one end of one of the rod bars 16 so that, if one of the rod bars 40 is moved to the right, the corresponding rod 16 is turned 40 about its axis and the valve connected to the latter opened. There are twelve rods 16 and an equal number of rod bars 40 arranged in four sets of three. The frame carrying the shift bars 33 also carries the rod bars 40, so that when the 45 frame is lifted both sets of bars are removed as a unit.

What is claimed is:

1. Bass action mechanism for accordions, comprising a series of rotatably mounted rods adapted 50 when turned about their axes to open the valves, a series of shift bars longitudinally and horizontally slidably transversely of said rods, a key at one end of each bar, a rod bar for each rod extending transversely of the shift bars and 55

slidable in the direction of movement of the latter, arms mounted on said rods engaging the corresponding rod bars, whereby a sliding movement of one of the latter turns its associated rod about 5 its axis, and projections on each shift bar adapted to engage one or more of the rod bars when the shift bar is moved by its key.

2. Bass action mechanism for accordions, comprising a series of rotatably mounted rods adapted 10 when turned about their axes to open the valves, a series of shift bars longitudinally and horizontally slidable transversely of said rods, a key at one end of each bar, a rod bar for each rod extending transversely of the shift bars and 15 slidable in the direction of movement of the latter, arms mounted on said rods adjacent the ends thereof engaging the ends of the corresponding rod bars, whereby a sliding movement of one of the latter turns its associated rod about its axis, the shift bars consisting of flat metal strips 20 arranged on edge and having portions cut away along their lower edge to receive the rod bars and to leave projections adapted to engage one or more of the rod bars when the shift bars are 25 moved by their keys.

3. Bass action mechanism for accordions, comprising a series of rotatably mounted rods adapted when turned about their axes to open the valves, a series of shift bars longitudinally and horizontally slidable transversely of said rods, 5 a key at one end of each bar, a rod bar for each rod extending transversely of the shift bars and slidable in the direction of movement of the latter, arms mounted on said rods adjacent the ends thereof engaging the ends of the corresponding rod bars, whereby a sliding movement of one of the latter turns its associated rod about its axis, the shift bars consisting of flat metal strips arranged on edge and having portions cut away 10 along their lower edge to receive the rod bars and to leave projections adapted to engage one or more of the rod bars when the shift bars are moved by their keys, and the rod bars consisting of flat metal strips arranged horizontally and 15 having portions cut away along one edge to permit certain keys to be operated without moving the rod bars and to leave projections for engagement with the shift bars of other keys. 20
